United States Patent Office

Des. 178,739

Patented Sept. 11, 1956

178,739

CABINET

Robert J. Slavsky and John R. Slavsky, Detroit, Mich., assignors to Shaw and Slavsky, Inc., Detroit, Mich., a corporation of Michigan

Application January 11, 1954, Serial No. 28,453

Term of patent 14 years

(Cl. D33—19)

Figure 1 is a perspective view of a cabinet showing our new design, illustrating the leaves in raised position and one drawer in open position;

We claim:

The ornamental design for a cabinet, as shown.
